UNITED STATES PATENT OFFICE.

HAYMAN KIRSCHENBAUM, OF NEW YORK, N. Y.

REENFORCED POCKET.

Application filed September 24, 1926. Serial No. 137,527.

This invention relates to garment pockets, and has especial reference to reenforcements for the pockets.

The principal object of the present invention is the provision of a substantial and effective reenforcement for a garment pocket applied at the opposite ends of the hand opening of the pocket to prevent tearing of the wall portions of the pocket sidewise with respect to the line of the pocket opening as well as endwise thereof.

The nature of the invention and its distinguishing features and advantages will appear when the following specification is read in connection with the accompanying drawing, in which:

Figure 1 is a view of a portion of a garment showing the hand opening of a pocket and the preferred form of reenforcement at each end of the hand opening.

Figure 2 is a sectional view taken on the line 2—2 of Figure 1.

Figure 3 is a view illustrating a modified form of reenforcement.

Referring now more particularly to Figures 1 and 2, it will be apparent, that there has been illustrated a portion of a garment which embodies a pocket, and the said pocket has the usual hand opening 11. The pocket illustrated is one which does not have associated therewith the usual closing flap, but it is to be understood that the reenforcements of the present invention may be applied to such flap type of pocket.

Hitherto, reenforcements have been applied to portions of the garment, or in other words the wall portions of a pocket to prevent tearing of the said portions, but while the reenforcements employed prevent tearing endwise, they do not prevent tearing of the wall portions of the pocket sidewise with respect to the line of the opening of the pocket.

Therefore, there is employed in accordance with the present invention, similar reenforcements 12 which may be of any preferred stout material, such as leather, which will be extended beyond the ends of the opening, and at opposite sides thereof. In Figure 1 there is shown a chevron or V-shaped reenforcement, there being one at each end of the opening 11. Each reenforcement 12 is attached to wall portions of the pocket by a

line of stitching 13 which extends along the marginal edge of the reenforcement. As applied, each reenforcement 12 will extend 55 in line with the pocket opening beyond the end or corner thereof as at 14, and will also extend at opposite sides of the opening as at 15 so as to provide portions within the region of the wall portions of the pocket between 60 the ends or corners of the hand opening 11. Under such provision the wall portions of the pocket at the opening 11 are prevented from tearing sidewise with respect to the pocket opening as well as endwise. 65

In accordance with the present invention other types of reenforcements may be used, such for instance, as the type shown in Figure 3. The reenforcement 16 shown in Figure 3 is circular and is secured to a wall 70 portion of the garment by a line of stitching 17 along the marginal edges thereof. The said reenforcement 16 is cut radially inward so that when applied will provide a portion 18 beyond the end of the hand opening of 75 the pocket and portions 19 at opposite sides of the opening of the pocket a distance from the end of the opening. The present type of reenforcement, like the reenforcement 12 prevents tearing sidewise as well as endwise 80 of pocket portions of the garment, with respect to the line of the opening of the pocket.

I claim:

1. A garment pocket reenforced at the corners of the hand opening of the pocket, 85 by flexible reenforcements respectively secured to outside garment portions of the pocket, and each of the reenforcements extended beyond its related corner and adjacent opposite sides of the hand opening inwardly from the corner.

2. A garment pocket reenforced by a flexible reenforcement at each corner of the hand opening of the pocket, each reenforcement sewed to an outside portion of the garment by a line of stitching along the marginal edges of the reenforcement, each of said reenforcements being of V-shape to provide a portion beyond its related corner of the hand opening and a portion adjacent 100 each side of the hand opening directed inwardly from the corner.

HAYMAN KIRSCHENBAUM.
